UNITED STATES PATENT OFFICE

2,470,620

UNITARY CLOSURE AND MASK FOR
CATHODE-RAY TUBES

Donald Jackson, Cambridge, England, assignor to
Pye Limited, Cambridge, England, a company
of Great Britain

Application November 15, 1946, Serial No. 710,119
In Great Britain September 27, 1945

2 Claims. (Cl. 178—7.5)

1

In television or like apparatus incorporating a cathode ray tube the dimensions of the enclosing cabinet are to a large extent determined by the dimensions of the cathode ray tube, as a result of which television apparatus, as hitherto manufactured, has been incorporated in relatively bulky and heavy cabinets. It is an object of the present invention to provide an arrangement whereby the cabinet may be considerably reduced in dimensions and weight with consequent saving of weight and raw material. A further object of the invention is to provide an improved mounting for the cathode ray tube in television or like apparatus. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the appended claims.

In this specification and the accompanying drawings, I have shown and described a preferred embodiment of the invention and various modifications thereof, but it is to be understood that these are not intended to be exhaustive nor limiting of the invention but, on the contrary, are given for purposes of illustration in order that others skilled in the art may fully understand the invention and the principles thereof and the manner of applying it in practical use so that they may modify and adapt it in various forms, each as may be best suited to the conditions of a particular use.

In the drawings,

Fig. 1 is a front perspective view of a television receiver embodying one form of the invention.

Fig. 2 is a top plan view of the receiver shown in Fig. 1 with the cabinet, however, partially broken away and certain portions shown in section.

Fig. 3 is a fragmentary section taken along line 3—3 of Fig. 2.

Fig. 4 is a side view analogous to that of Fig. 3, showing in partial section a modified form of cover for the front end of the cathode ray tube.

Fig. 5 similarly is a sectional view of a further modification of the cover, and

Fig. 6 is a fragmentary section taken along line 6—6 of Fig. 2, showing the mounting for the front end of the cathode ray tube.

As earlier mentioned, television and other apparatus incorporating a cathode ray tube has hitherto been characterised by an undesirable bulkiness and heaviness of the enclosing case or

2

cabinet, due principally to the relatively great depth of cabinet required to enclose the relatively long cathode ray tube. These undesirable features are accentuated in television receivers, since not only has the tube itself to be accommodated, but also the sloping framing mask and protective window customarily provided over the front end, i. e. the screen end, of the tube.

In order to mitigate the above-noted conditions, in accordance with the present invention, the cathode ray tube is carried by a chassis with the front end or screen portion of the tube projecting beyond the front edge of the chassis, and the enclosing cabinet is made with general dimensions sufficient to accommodate the depth of the chassis, and is provided with an opening in its front wall through which the front of the cathode ray tube may project, the opening being covered by a housing of sufficient dimensions to enclose the front end of the tube. Preferably, the housing is made only large enough to enclose and protect the projecting portion of the cathode ray tube. The front of the housing incorporates a window through which the fluorescent screen on the front end of the tube may be viewed. Thus, the cabinet is provided with a projecting portion which may be likened to a bay window, in which the front end of the cathode ray tube is accommodated. In this manner, the general overall depth of the cabinet may be considerably reduced without the rear end of the cathode ray tube having to project from the back of the cabinet, whilst also the picture viewed on the screen of the tube stands forward from the cabinet in a pleasing manner.

As the front end of the tube is of generally circular shape, the projecting bay window housing may be made substantially square to circumscribe the front end of the tube, and may be made with or without curved tops and sides. The housing may be internally shaped to embrace the front end of the tube or a rubber or like gasket embracing the tube. The housing may also be formed or provided with a masking frame corresponding to the size of the picture to be displayed. Since the picture displayed in a television receiver is generally of oblong form, the projecting housing may be of similar form and be provided with bulbous portions at its upper and lower surfaces to embrace the top and bottom edges of the front of the cathode ray tube.

Referring first to Figs. 1 and 2, the television receiver illustrated has a cabinet 10 of general dimensions sufficient to accommodate the receiver chassis, denoted generally by 11. The cathode ray tube 12 is supported at the rear by a saddle

13 mounted on the chassis, and the front end of the tube is supported by a saddle and strap arrangement generally denoted by 14 in Fig. 2, which will be more fully described hereinafter. The tube 12 is mounted so that its front end overhangs the front edge 15 of the chassis, as seen in Fig. 2, and the front end of the tube is fitted with an embracing rubber gasket ring 16 utilised in the mounting of the front end of the tube. In this embodiment, the gasket 16 incorporates integrally therewith an oblong sloping masking frame 17 corresponding to the size of the picture to be displayed on the screen 18 of the tube. The ring 16 and frame 17 are formed as a single rubber moulding. It will be appreciated from a consideration of Fig. 2 that the frame 17 projects forwardly beyond the front end of the tube 12.

The cabinet 10 has an opening 19 in its front wall through which the front end of tube 12 carrying frame 17 protrudes. A housing 20 fits over and closes the opening 19, so as to enclose and accommodate the projecting front end of tube 12 and the frame 17. The housing is shown as being generally oblong, conforming to the shape of the picture to be displayed, and in order to accommodate the top and bottom excess portions of the front of the tube 12 which are masked by frame 17, the housing 20 is formed with upper and lower bulbous portions 21 for that purpose, as more clearly seen in Fig. 3. The housing 20 may be made of any suitable material, such as wood, plastic or metal, and is formed with a window in its front through which the tube screen 18 may be viewed. In the embodiment depicted in Figs. 1 to 3, the housing 20 is open-fronted and formed at its front with a seating recess 22 into which a transparent protective plate 23, e. g. of glass or a plastic, is fitted to cover the front of tube 12, the plate 23 being held in place by a bezel 24 into which are fixed bolts 25 or the like which extend from the rear of the bezel and pass through the housing 20 into the interior of cabinet 10 where they are nutted or otherwise secured to an anchorage on the chassis 11 to hold the housing assembly together in place on the front of the cabinet.

In the receiver illustrated, the loudspeaker 26 for reproducing the sound accompanying the picture displayed on tube screen 18 is shown disposed to one side of the projecting housing 20. The loudspeaker may, however, be disposed above or below the housing 20, if so desired, for example in a console model. The necessary sound aperture provided in the cabinet front wall in front of the loudspeaker may be covered with a grille or fret member 27 which may incorporate a movable shutter 28 or the like behind which some of the preset controls (not shown) of the receiver may be disposed, so that when the shutter is closed the controls are hidden. The loudspeaker facing 27 may, for example and as shown in Fig. 1, comprise a rectangular member having the shutter 28 slideable up and down in the lower region thereof, the shutter having a suitable fingerhold 29 for operating the same.

In the described embodiment, the frame 17 is incorporated with the gasket ring 16. Other arrangements are, however, possible. For example, in a modification as illustrated in Fig. 4, the masking frame 17a is incorporated with the housing 20a, and these may be made integral, such as by moulding the same as a unit in a plastic material, the unit being formed with a recess 22a to receive a transparent window plate as in the

previous embodiment. In this modification, the gasket ring performs only its function in the mounting of the front end of tube 12.

In a further modification, the projecting housing, masking frame and protective window may all be made integrally as a single unit 30, as illustrated in Fig. 5, by moulding the same in a transparent plastic. Such unit may, for example, be pressed from transparent plastic sheet stock, and the formed unit may be rendered opaque, e. g. by spraying, on the rear surfaces of the housing portion 20b and masking frame portion 17b thereof, the portion 23b constituting the protective window plate being, of course, left transparent. The window portion 23b is shaped to closely fit the curved front face of the tube 12, as it has been found that this affords better protection than a separate glass plate.

A further feature of the invention consists in the arrangement for mounting and supporting the front end of the cathode ray tube, as best seen in Fig. 6. As earlier mentioned, the front of the tube 12 is fitted with an embracing gasket ring 16 of rubber or like material. This gasket has an inwardly projecting flange portion 31 (Fig. 3) and is internally shaped so that it snugly fits around the front periphery of the tube. The ring 16 rests in a saddle structure carried from the chassis, and is secured therein by an embracing strap which is secured to the saddle.

As shown, the saddle structure may comprise two angle plate brackets 32 each secured by one plate 33 thereof to the front wall 34 of the chassis 11 so that the other plate 35 of each bracket 33 extends outwardly and upwardly to a point adjacent the end of the cathode ray tube 12 which projects beyond the front wall 34 of the chassis 11. Between the upper ends of the plates 35 of these two brackets is supported a curved strip member 36 constituting the saddle, which is secured to the plates 35, as by rivetting or welding. The ends of the saddle strip are bent outwardly to form fixing flanges 37 provided with fixing holes. A similar curved strip member 38 constituting the clamping strap is fitted over the top half of the rubber ring 16, and is likewise formed at its ends with apertured fixing flanges 39; the strap being secured to the saddle by nutted bolts 40 passed through the holes in the flanges 37 and 39.

The gasket ring 16 is preferably made of thick flexible material and is provided with one or more axial slots (not shown) so that it can be tightened by the clamping strap and saddle against the tube without actually compressing the rubber of the gasket to any great extent. Preferably two such slots are provided at diametrically opposite points of the gasket ring.

I claim:

1. A closure for mounting on a television receiver cabinet in closing relation to an opening therein and in front of the cathode ray tube of the receiver, said closure comprising a one-piece member of transparent material having a front portion and a flange portion forming a side wall extending around the periphery of said front portion, said flange portion and a peripheral marginal portion of said front portion being rendered opaque and forming a masking frame surrounding a transparent window portion of said front portion, said transparent window portion being outwardly curved and said peripheral marginal portion being flared, diverging outwardly from said outwardly curved window portion.
2. A closure for mounting on a television re-

ceiver cabinet in closing relation to an opening therein and in front of the cathode ray tube of the receiver, said closure consisting of a one-piece moulding of transparent material including a front portion and a flange portion forming a side wall extending around the periphery of said front portion, said front portion comprising a portion which is of outwardly curved cross-sectional configuration and merges into a peripheral marginal portion surrounding said outwardly curved portion, said marginal portion being flared divergently outwardly from said curved portion, a coating of opaque material applied to said flange portion and to said marginal portion to render said flange portion and said marginal portion opaque to form a masking

frame surrounding said curved portion of said front portion which is left transparent to form a viewing window.

DONALD JACKSON.
